UNITED STATES PATENT OFFICE.

ALFRED B. BELL, OF PHILADELPHIA, PENNSYLVANIA, ASSIGNOR TO HALE AND KILBURN COMPANY, OF PHILADELPHIA, PENNSYLVANIA, A CORPORATION OF DELAWARE.

HINGE AND CASING THEREFOR.

1,254,020.

Specification of Letters Patent. Patented Jan. 22, 1918.

Application filed March 23, 1915. Serial No. 16,322.

To all whom it may concern:

Be it known that I, ALFRED B. BELL, a citizen of the United States, residing at Philadelphia, in the county of Philadelphia and State of Pennsylvania, have invented 5 certain new and useful Improvements in Hinges and Casings Therefor, of which the following is a specification.

My invention relates particularly to the 10 construction of hinge casings and the parts coating therewith such as are adapted to be applied to the bottom edge of drop doors, which are adapted to swing downwardly and outwardly to open position. My invention 15 relates to the character of construction disclosed in the patent of Robert B. Caverly and Alfred B. Bell, drop door hinges, No. 1,176,734, dated March 28, 1916. In the construction referred to, a hinge 20 cover or casing is provided, preferably formed of sheet-metal, with flanges secured to the front of the range or frame member, the pivot pin of the hinge being supported in openings in the side walls of the casing, the pivot pin having arms integral therewith secured to a bottom corner of the door. An inwardly directed stop or lug is provided within the casing, serving as a stop 25 to coact with a member on the pivot pin having a projection which engages the stop member in the casing when the door is in open position, a spring also being provided within the casing to resist opening movement of the door. My invention constitutes 30 an improvement upon the devices referred to in the means whereby the hinge casing is secured to the frame. I provide one of the flanges of the hinge casing with a screw-hole and one or more other flanges with slots 35 therethrough so positioned and shaped as to permit engagement of the slot or slots with a headed pin or pins mounted in the frame, by a simple movement of the casing parallel to the frame to engage the pin or pins. I 40 prefer to provide the screw-hole in the upper flange of the casing. The slot referred to may be an open-ended slot formed in the edge portion of one of the flanges, or it may be a slot formed with the shape of a key-hole, having a comparatively wide, and a 45 narrower portion, whereby the casing may be mounted by moving the same against the frame with the head of the pin referred to extending through the wider portion of the 50 slot, and then moving the casing parallel 55

to the frame to engage the shank of the pin in the narrower portion of the slot. Or both the open-ended slot and the keyhole-shaped slot may be used in different flanges at the same time, this constituting my preferred 60 construction. By these means, the hinge casing may be very easily and quickly mounted in position, and removed, with the necessity for securing or removing only a single screw or bolt for each hinge casing. 65

In order that a clearer understanding of my invention may be had, attention is hereby directed to the accompanying drawings forming part of this specification and showing certain embodiments of my invention. 70 In the drawings, Figure 1 represents a partial front elevation of a door pivoted to a supporting frame by a pair of hinges, Fig. 2 represents, on an enlarged scale, one corner of the door and the hinge construction 75 coacting therewith, the hinge cover being shown in section, and the flanges of the hinge casing being of a different form from those shown in Fig. 1, Fig. 3 is a transverse vertical section on line 3—3 of Fig. 2 and 80 Fig. 4 is a transverse vertical section on line 4—4 of Fig. 1, on an enlarged scale.

The door 1 is pivoted adjacent its lower edge to the frame member 2, which may be the front sheet of a gas range. Hinge covers or casings 3, 3 are secured to the frame member adjacent the lower corners of the door, the hinge casings preferably being formed of sheet-metal pressed to the shape illustrated. The pivot members are preferably each formed with vertical and horizontal flanges 4, 4 and 5, 5, secured to the side and bottom edges of the door 1. Each pivot member is provided with a pivot pin 6, integral therewith, having cylindrical 90 portions rotatably mounted in the side-walls of the hinge casings as shown. Each pin 6 is also preferably provided with a squared portion 7 on which is mounted a disk 8 having a square hole therethrough, disk 8 100 having a projection 9 thereon adapted to contact a lug 10 extending inwardly of the casing, to act as a stop and hold the door in lowered position. A spiral spring 11 is coiled about each pivot pin within its casing 105 to resist the opening movement of the door, one end of the spring being secured in disk 8 and the other end of the spring being inserted in a hole in frame member 2 as shown in Fig. 4. The stop member 10 with- 110

in the casing may be a separate piece bent to an angle and welded within the casing as shown in Fig. 3, or it may be formed integral with the casing, for example, by slitting the metal of the casing and pressing it inwardly to form a stop as shown at 10' in Fig. 4.

The hinge casing is preferably secured to the frame in the manner indicated in Figs. 10 1 and 4 in which the casing is provided with an upwardly extending flange 12 and a downwardly extending flange 13, above and below the body of the casing respectively, and a side flange 14 extending inwardly of 15 the frame from a side of the casing. The top flange 12 is provided with a screw-hole through which a screw or bolt 15 may be passed and screwed into the frame 2. The bottom flange 13 is illustrated as provided with the keyhole slot 16 having a comparatively large opening at the bottom thereof and a narrower slot extending thereto at the upper part. The flange 14 is provided with a slot 17 formed in the lower edge 25 thereof, slots 16 and 17 being adapted to engage headed pins 18 and 19, respectively, projecting outwardly from the frame 2. When a hinge casing is to be mounted in position, it is only necessary to press the 30 same against the front of the frame with the head of pin 18 projecting through the large opening of keyhole slot 16, when the casing may be rocked into position to bring the slot 17 into line with headed pin 19. 35 The casing is then pressed downwardly to cause pin 18 to engage within the narrow portion of the keyhole slot and pin 19 to en-

gage within the open-ended slot 17. The screw 15 may then be secured in place, the hinge casing thus being quickly and securely positioned with the aid of only one removable screw or bolt.

In Figs. 2 and 3 is shown a modification in which the bottom slot 13 is omitted, the casing being positioned and secured only by 45 the engagement of headed pin 19 in slot 17 of the side flange 14 and the screw or bolt 15 extending through flange 12. It is obvious that slots of the character of the open-ended slot 17 or the keyhole slot 16 may be used in 50 either one or both of several flanges, or that slots 16 and 17 may be interchanged, or that slots of different configuration may be used, operating in the same manner as that described.

Having now particularly described my invention, what I claim and desire to protect by Letters Patent is as follows:—

In a hinge construction, a hinge casing having an inclosed portion adapted to receive a pivot pin and spring, with side walls pierced to receive the pin, and upper, lower and side flanges, one of the same having a screw-hole therethrough, another having a keyhole-shaped slot therethrough, and a third having an open-ended slot in an edge thereof, substantially as set forth.

This specification signed and witnessed this 19th day of March, 1915.

ALFRED B. BELL.
